UNITED STATES PATENT OFFICE.

HENRY G. BUTLER, OF HOUSTON, TEXAS.

METHOD OF AND APPARATUS FOR BURNING BALLAST.

Application filed July 6, 1925. Serial No. 41,584.

To all whom it may concern:

Be it known that I, HENRY G. BUTLER, a citizen of the United States, and a resident of Houston, in the county of Harris and State of Texas, have invented a certain new and useful Improvement in Methods of and Apparatus for Burning Ballast, of which the following is a specification.

My invention relates to improvements in methods of and apparatus for burning ballast.

It relates particularly to the burning of raw earth for the production of railway ballast.

One of the objects of my invention is to provide a novel method of burning raw earth to produce ballast, which affords economical operation, large production, which produces uniform and a superior product, and which permits of the use of an inexpensive apparatus for the burning of raw earth.

My invention provides further a novel apparatus for carrying into effect my improved method, which embodies a simple construction, which is durable, not liable to get out of order, and which requires a relative small amount of labor.

My invention provides still further novel means for effecting a continuous production, novel and efficient means for feeding along the pile of earth as it is burned, and novel means for effecting combustion in the pile.

The novel features of my invention are hereinafter fully described and claimed.

In the accompanying drawings, which illustrate my improved apparatus for carrying into effect my improved method,

Fig. 1 is a plan view of a battery of two kilns which embody my improved apparatus.

Fig. 2 is an enlarged cross section, parts omitted and parts broken away, on the line 2-2 of Fig. 4.

Fig. 3 is an enlarged plan view, parts being omitted and parts being broken away, of one of my improved kilns.

Fig. 4 is an enlarged sectional view on the line 4-4 of Fig. 1.

Fig. 5 is a still further enlarged cross section, parts being omitted, on the line 5-5 of Fig. 4.

Similar reference characters designate similar parts in the different views.

In the preferred form of my apparatus, the kiln is provided with an air chamber adapted to hold compressed air, and which is provided with side walls 1, a lower end

wall 2, and an upper end wall 3. The wall 2 is located in a ditch 4 into which the burned ballast from the kilns is dumped for subsequent removal.

The air chamber is provided with a ceiling comprising two sets of longitudinal supporting members adapted to support the raw earth to be burned, and which may comprise inverted T rails 5 and 6, which preferably incline downwardly toward the ditch 4. The rails 5 are disposed above and spaced apart from and overlapping the adjacent rail 6 of the other set. The lower rails 6 are disposed in pairs, the rails of each pair having their bases adjoining each other, and the pairs being spaced apart, thereby affording air passage means between the rails 5 and 6 by which air under pressure may pass from the air chamber through the pile of earth which lies on the rails 5 and 6.

The side walls 1 of the air chamber extend above, say a foot or two feet above the rails 5, thus affording a support for the sides of the pile of earth on the rails 5 and 6.

The upper and lower ends of the rails 6 are respectively supported on the walls 3 and 2. In the air chamber may be provided pillars 7 having mounted on them transverse bars 7' which provide intermediate supports for the rails 6.

The rails 5 are mounted in grooved rollers 8, some of which are supported on brackets 9 carried by the walls 2 and 3, and some supported on cross bars 8' carried by the side walls 1 and pillars 10 located in the air chamber.

The rails 5 are tied together by cross bars 11 to which are secured angle bars 12 disposed in pairs, the bars of said pairs being respectively riveted to opposite sides of the rails 5. The rails 5 are longitudinally reciprocated by means of segmental gears 13 which respectively mesh with longitudinal racks 14 respectively secured to some of the bars 5 at the under side thereof, the gears 13 being rigidly secured to a horizontal transverse rock shaft 15.

Rigidly secured also to the rock shaft 15 are segmental gears 16 each having an arm 17. Respectively pivoted to said arms are reciprocative bars 18 to which reciprocation may be provided jointly by any suitable means, not shown. The gears 16 also respectively mesh with racks 14 fastened to the under side of two of the rails 5. The rock shaft is pivotally supported at its ends

in the side walls 1 of the air chamber, and it may also be supported intermediate of its ends in pillars 19 in the air chamber.

In one side wall 1 may be provided a door 20 for entrance and egress with respect to the air chamber. The lower wall 2 of said chamber may be provided with one or more clean out openings 21, normally closed by doors 22.

10 For providing air under pressure in the air chamber, and for blowing air upwardly between the rails 5 and 6 and through the pile of earth 23 to be burned, for effecting complete combustion, there is in the air chamber a transverse air pipe 24 which extends through one wall 1 and which is connected to any suitable source of supply of compressed air, such as a blower, not shown.

Connected to the air pipe 24 are longitudinal air pipes 25 from each of which upwardly extend pipes 26 which discharge upwardly between the rails 6 and 5.

For engaging and pushing against the upper end of the pile 23 of raw earth to be burned, when the bars 5 are forced downwardly, there is fastened to the rails 5 at their upper sides and end portions an upwardly extending pusher member comprising an angle plate 27, which is disposed transversely and has one flange secured to the upper sides of the rails 5, and the other flange of which extends upwardly.

In practice, there may be a battery of kilns disposed side by side and spaced apart, as shown in Fig. 1, in which two kilns are shown, both of which discharge into the ditch 4. The kilns may all be constructed alike, so that the description above may be applied to each. The kilns may also all be operated alike, so that a description of the operation of one will suffice for each.

In the preliminary charging of the kiln, raw earth in contact with fuel, preferably coal, and preferably mixed therewith is dumped upon the rails 5 and 6 until the pile 23 reaches to about two thirds of the lengths of the rails from the lower ends thereof, and to the depth, say six feet, which the pile is to be. Ignited fuel is then placed on the upper bare portions of the rails 5 and 6 and upon such fuel fresh raw earth mixed with coal is dumped until the kiln is filled to and wholly covering the upper side of the pusher plate 27. The compressed air is then permitted to enter the pipe 24 from its source of supply, the air passing then through the pipes 25 to and through the pipes 26 by which the air is discharged into the air chamber and between the rails 5 and 6. The air chamber is made as tight as possible so as to afford small leakage.

After the fire has been well started, and is burning the coal mixed with the earth, the operating bars 18 are reciprocated three or four times, thereby reciprocating the ceiling

bars 5 a like number of times, through the intermediary of the racks 14, gears 13 and 16, rock shaft 15, and arms 17. As the bars 5 are moved downwardly, the pile of raw earth mixed with coal is carried downwardly, the inclination of the bars 5 and 6 assisting in this movement, and the pusher member 27 bearing against the rear upper end of the pile 23. A portion of the front lower end of the pile 23 is dumped into the ditch 4. As the bars 5 in their reciprocation, move upwardly, they will carry with them sufficient ignited material to ignite the fresh mixed earth and coal, which is now dumped upon the rails 5 and 6 at the upper end of the pile to and covering the plate 27.

The bars 5 are given the series of reciprocations above described about hourly, the length of each reciprocation being such that the earth at the upper end of the pile will be on the rails 5 and 6 about 24 hours before it is a finished cooled product. The first increment of earth which was put in the kiln to the extent of two thirds of the length of the pile, will be discharged into the ditch 4 and then reburned. The earth which was afterwards deposited in the kiln will be completely burned after it has traveled about two thirds downwardly in the kiln, where combustion will have been completed. This finished product will then cool during the remainder of its downward journey until it is discharged into the ditch 4, when it will have cooled sufficiently to be handled. It may then be removed from the ditch by any suitable means, and will be ready for use.

When the supporting rails 5 are upwardly moved, they will pull upwardly sufficient burning material to ignite the fresh material added to the upper end of the pile 23, after the pile has been moved downwardly and left a vacancy between the pile and the push plate 27, as shown in Fig. 4. The fresh raw earth and coal mixed therewith will fill the vacancy and prevent leakage of air at that point excepting through the pile.

By using the air chamber and compressed air therein, a bountiful supply of air for combustion is afforded in the pile 23, and the pressure of air in the chamber against the earth lying on the rails 5 and 6 will tend to prevent material passing downwardly into the air chamber. The arrangement of the rails 5 overlapping the rails 6 also tends to prevent earth passing downwardly into the air chamber.

By having the surface of the rails 6 having a supporting area greater than the supporting surface of the rails 5, as shown, the upward movement of the latter will cause only enough ignited material to be upwardly drawn to ignite the freshly deposited material at the upper end of the pile. The slanting supporting surfaces of the rails 5

and 6, assists, by the gravity of the pile, the downward feeding movement. An inclination of about fifteen degrees has been found to be a suitable slant for the purpose.

5 The number and length of reciprocations of the rails 5 for each downward hourly forward feeding operation of the pile may be varied, as may be lapse of time between the feeding operations, the same to be determined by the character of the material which is being burned. Also the amount of fuel to be mixed with the raw earth to effect proper burning of the latter may be determined by trial.

15 The intensity of the fire may also be varied to suit the material to be used, so that the product may be of the nature of brick or even subjected to incipient or more complete fusion. The amount of fuel used and 20 the volume of air employed should be such that complete combustion has been effected and the earth burned to the desired extent before the finished product is discharged from the kiln into the ditch 4, so that no 25 partly burned material is dumped into the ditch, excepting at the initial starting of the kiln, and so that the finished discharged material is cool enough to be conveniently handled.

30 Any suitable means may be employed for depositing the mixed raw earth and fuel into the kiln, and if desired, the earth and fuel may be deposited in alternate layers in the kiln instead being intermingled as by mixing.

I do not limit my invention to the structure nor specific steps described, as many modifications may be made, within the scope of the appended claims, without departing from the spirit of my invention.

40 What I claim is:—

1. The method of burning ballast consisting in forcing air under pressure through a pile of raw earth in contact with burning fuel and employing gravity to feed the pile along.

2. The method of burning ballast consisting in forcing air under pressure through raw earth mixed with burning fuel and feeding the mixture downwardly during the burning operation.

3. The method of burning ballast consisting in feeding downwardly raw earth in contact with burning fuel, adding new raw earth and fuel to that being fed, and forcing air under pressure through the mass that is being fed along.

4. The method of burning ballast consisting in feeding downwardly raw earth mixed with burning fuel, adding new raw earth and fuel to that being fed along, and forcing air under pressure through the mass that is being fed along.

5. The method of burning ballast consisting in forming into a pile raw earth in con-

tact with burning fuel, feeding the pile downwardly, adding new raw earth and fuel to the rear end of said pile, and forcing air through the pile.

6. The method of burning ballast consisting in forming into a pile raw earth mixed with burning fuel, feeding the pile downwardly, adding raw earth and fuel to the rear end of the pile, and forcing air through the mass.

7. The method of burning ballast consisting in forming into a pile raw earth in contact with burning fuel, disposing the pile on an inclined surface, feeding the pile endwise downwardly on said inclined surface, adding raw earth and fuel to the upper end of the pile, and forcing air through the pile.

8. The method of burning ballast consisting in forming into a pile raw earth mixed with burning fuel, disposing the pile on an inclined surface, feeding the pile endwise downwardly on said inclined surface, adding raw earth and fuel to the upper end of the pile, and forcing air through the pile.

9. The method of burning ballast consisting in forming into a pile raw earth mixed with burning fuel, feeding the pile downwardly, and adding raw earth and fuel to the upper end of the pile.

10. The method of burning ballast consisting in forming into a pile raw earth mixed with burning fuel on an inclined surface, feeding the pile downwardly on said inclined surface, and adding raw earth and fuel to the upper end of the pile.

11. The method of burning ballast consisting in forming into a pile raw earth and burning fuel in contact therewith, feeding the pile downwardly, discharging the burnt earth from the lower end of the pile after combustion has been completed, and adding to the upper end of the pile fresh earth and fuel.

12. The method of burning ballast consisting in forming into a pile raw earth mixed with burning fuel, feeding the pile downwardly, discharging the burnt earth from the lower end of the pile after combustion has been completed, and adding to the upper end of the pile fresh earth and fuel.

13. The method consisting in forming on an inclined surface a pile of raw earth and burning fuel in contact therewith, feeding the pile endwise downwardly on said inclined surface, discharging from said surface the burnt earth after combustion has been completed, and feeding fresh raw earth and fuel to the upper end of the pile.

14. The method consisting in forming on an inclined surface a pile of raw earth and burning fuel in contact therewith, feeding the pile endwise downwardly, discharging the burnt earth from the lower end of the pile after combustion has been completed,

adding fresh earth and fuel to the upper end of the pile, and forcing air through the pile.

15. The method consisting in forming on an inclined surface a pile of raw earth mixed with burning fuel, feeding the pile endwise downwardly, discharging the burnt earth from the lower end of the pile after combustion has been completed, adding fresh earth and fuel to the upper end of the pile, and forcing air through the pile.

16. In a ballast kiln, an air chamber having a ceiling provided with air passage means and provided with a reciprocative portion adapted to support a pile of earth to be burned, said portion having means for engaging and pushing against one end of the pile, means for reciprocating said portion endwise of said pile, and means for forcing air into said chamber.

17. In a ballast kiln, a reciprocative support adapted to support a pile of earth to be burned and having means for engaging and pushing against one end of said pile, means for reciprocating said support, and means adapted to force air through said pile.

18. In a ballast kiln, a reciprocative support adapted to support a pile of earth to be burned and provided therethrough with air passage means and having means adapted to engage and push against one end of said pile, means for reciprocating said support, and means for supplying said air passage means with air under pressure.

19. In a ballast kiln, a reciprocative support adapted to support a pile of earth to be burned and comprising longitudinal bars longitudinally reciprocative and spaced from each other and an upstanding pusher member carried by said bars at the rear thereof and adapted to engage and push against the rear end of said pile.

20. In a ballast kiln, a reciprocative support adapted to support a pile of earth to be burned and comprising longitudinally reciprocative bars spaced from each other and an upstanding pusher member carried by said bars at the rear ends thereof and adapted to engage and push against the rear end of said pile, and means for forcing air through said pile and between said bars.

21. In a ballast kiln, a support adapted to support a pile of earth to be burned comprising two sets of supporting members, the members of one set being disposed above and spaced apart from and overlapping the members of the other set.

22. In a ballast kiln, two sets of members adapted to support a pile of earth to be burned, the members of each set being spaced from each other, and the members of one set being above and spaced from and overlapping the members of the other set, the members of the upper set being reciprocative.

23. In a ballast kiln, two sets of members adapted to support a pile of earth to be burned, the members of each set being spaced from each other, and the members of one set being above and spaced from and overlapping the members of the other set, the members of the upper set being reciprocative, and a pusher member carried by the upper members at the rear ends thereof and adapted to engage and push against the rear end of said pile.

24. In a ballast kiln, two sets of members adapted to support a pile of earth to be burned, the members of each set being spaced from each other, and the members of one set being above and spaced from and overlapping the members of the other set, the members of the upper set being reciprocative, a pusher member carried by the members of the upper set adapted to engage and push against the rear end of said pile, and means for forcing air through said pile and between said members of said sets.

25. In a ballast kiln, a reciprocative support having inclined surfaces adapted to support a pile of earth to be burned, and a pusher member carried by said support and adapted to engage and push against the rear end of said pile.

26. In a ballast kiln, a reciprocative support having inclined surfaces adapted to support a pile of earth to be burned, a pusher member carried by said support and adapted to push against the rear end of said pile, and means for forcing air through said pile.

27. In a ballast kiln, an air chamber having a ceiling adapted to support a pile of earth to be burned and having air passage means therethrough, a portion of the ceiling being reciprocative lengthwise of said pile, the chamber having side walls which extend above the ceiling at the sides of the pile, said reciprocative portion having means for engaging and pushing against the rear end of the pile.

28. In a ballast kiln, an air chamber having an inclined ceiling adapted to support a pile of earth to be burned and having air passage means therethrough, a portion of the ceiling being reciprocative lengthwise of said pile.

29. In a ballast kiln, an air chamber having an inclined ceiling adapted to support a pile of earth to be burned and having air passage means therethrough, a portion of the ceiling being reciprocative lengthwise of the pile in the direction of the inclination, the reciprocative portion having means for engaging and pushing against the rear upper end of said pile.

30. In a ballast kiln, an air chamber having an inclined ceiling adapted to support a pile of earth to be burned and having air passage means therethrough, a portion of

the ceiling being reciprocal in the direction of said inclination and lengthwise of said pile and having means for engaging and pushing downwardly against said pile.

- 5 31. In a ballast kiln, an air chamber having an inclined ceiling adapted to support a pile of earth to be burned and having air passage means therethrough, a portion of the ceiling being reciprocal in the direction of said inclination and lengthwise of said pile and having means for engaging and pushing downwardly against said pile, the chamber having side walls extending above said ceiling at the sides of said pile.
- 10 32. In a ballast kiln, an air chamber having a ceiling comprising two sets of supporting members, the members of one set being above and spaced from the members of the other set, some of said members of the other set being spaced from each other and overlapped by adjacent ones of the upper members, the upper members being reciprocal lengthwise of a pile of earth to be burned which is adapted to be supported by said ceiling members.
- 15 33. In a ballast kiln, an air chamber having a ceiling comprising two sets of supporting members adapted to support a pile of earth to be burned, said members being inclined in the direction of length of said pile, the members of one set being above and

spaced from and overlapping adjacent ones of the under members, some of the latter being spaced from each other, the members of the upper set being reciprocal in the direction of said inclination.

34. In a ballast kiln, an air chamber having an inclined ceiling adapted to support a pile of earth to be burned and comprising two sets of inclined supporting members, the members of one set being above and spaced from and overlapping the adjacent members of the other set, said upper members being reciprocal in the direction of the said inclination and having means for engaging and pushing downwardly against said pile.

35. In a ballast kiln, an air chamber having an inclined ceiling adapted to support a pile of earth to be burned and comprising two sets of inclined supporting members, the members of one set being above and spaced from and overlapping the adjacent members of the other set, the upper members being reciprocal in the direction of said inclination, and an upwardly extending transverse member secured to said upper members and adapted to engage the rear upper end of said pile.

In testimony whereof I have signed my name to this specification.

HENRY G. BUTLER.
